UNITED STATES PATENT OFFICE.

ALBERT E. NAUGLE, OF PITMAN, NEW JERSEY.

ENVELOPE AND METHOD OF MAKING SAME.

Application filed January 5, 1926. Serial No. 79,322.

My invention relates to envelopes and to that class of envelopes intended to be used unsealed and with means to retain the contents against accidental egress.

5 While adapted for any purpose to which these unsealed envelopes are ordinarily used, my invention is particularly intended for envelopes intended to hold heavy articles such as coins, small machine elements and 10 the like.

It is old to provide envelopes of this character with a turned in flap or flaps intended to retain the enclosed article against accidental egress but, when used with contents 15 of a heavy nature such as coins, these have proved unsatisfactory as the flats are easily distorted by the weight of the contents causing said flaps to buckle and leave an orifice through which the contents may pass out.

20 It is also old in the art to provide such flaps with stiffening members to prevent such buckling but this has usually involved the addition of other material to the paper blank from which envelopes are customarily produced and in addition it has caused an 25 undue thickness at one end of the envelope making envelopes so formed inconvenient to stack.

30 In paying large groups of employees, as in factories, it is customary to make up a payroll sheet on which is indicated the number of bills and coins of convenient denomination required to constitute each employee's pay. These are listed in columns and the 35 columns, when added up, give the number required of each bill or coin to meet the payroll. The currency and coin is drawn from the bank in butildes and bags and placed in envelopes bearing the employees' 40 names or number, the required number of bills and coins going into each envelope being determined from the payroll sheet.

45 If the envelopes are all filled without excess or shortage in the money drawn to meet the payroll, this is usually accepted as proof of the correctness of the distribution. In making up payrolls, however, a shortage or excess is not infrequent and it is very desirable to use a type of container which will 50 securely hold the currency and coin during handling but which may be emptied quickly in the event it becomes necessary to recheck the payroll.

55 An object of my invention, therefore, is to provide an envelope which will securely hold its contents without sealing.

A further object of my invention is to provide such an envelope as will hold heavy articles without distortion of the closing means in case the articles are shaken therein. 60

A further object of my invention is to provide such a device in which the contents of the envelope may be expeditiously removed if desired without destruction of the envelope. 65

A further object of my invention is to provide such a device constructed wholly from a paper blank and adhesive material as commonly used in the manufacture of envelopes. 70

A further object of my invention is to provide an open edge envelope, reinforced at the opening, produced from a unitary blank of sheet material. 75

My invention is capable of embodiment in a variety of forms within the spirit of the claims forming part hereof, one of which for purposes of illustration is shown in the accompanying drawings. 80

In the drawings:

Figure 1 is a side elevation of the device partly broken away to show internal structure.

Figure 2 is a section on line 2-2 of Figure 1. 85

Figure 3 is a plan on a reduced scale of the blank from which my device is formed.

Referring first to the blank shown in Figure 3:

1 is one of the flat sides of the envelope, 90 and 2 is the other flat side.

Side 1 has edges 3, 4, 5 and 6 and side 2 has edges 7, 8, 9 and 10, edges 4 and 10 being connected in the blank. 95

On the edge 6 is a tab 11 and on edge 5 is a tab 12. These tabs may be folded relative to side 1 and be attached to side 2 by adhesive or otherwise in a manner well understood in this art. 100

On edge 3 is a flap 13 and on edge 7 is a flap 14, these flaps being preferably identical in form and dimension while in the blank form. 105

On flap 13 is a score or other mark 15 and on flap 14 is a similar mark 16, the mark 16 being nearer to the edge 7 than is the mark 15 to the edge 3. Thus for a purpose hereinafter to be explained, as shown, these flaps are preferably somewhat narrower at their outer ends 17 and 18 than at the edges 3 and 7. 110

To form the envelope from the blank, the

edge 17 is folded over the body of the flap 13 a short distance and then is continuously folded or rolled until the roll thus formed is carried down to the mark 15. The edge 18 5 is similarly folded or rolled until the roll thus formed is carried down to the mark 16. In making this roll or fold, it is desirable that the width of the roll shall be slightly less than the perpendicular distance from the 10 line 15 to an extension of the line 16. Before rolling, the flap is preferably coated with adhesive so that the rolls thus formed will retain their shape and the unrolled portion of the flap will adhere to the inner walls 15 of the envelope.

When rolled in the manner indicated, the flaps 13 and 14 will be provided respectively with ridge members 19 and 20 formed by the rolled portions of the flaps.

20 To form the envelope from the blank after rolling the flaps to produce the ridge members, the flaps 13 and 14 are turned downward over the sides 1 and 2 of the blank and the blank is then folded along the line 4—10 25 and the tabs 11 and 12 folded over the side 1 and secured thereto by adhesive or otherwise.

The ridge members are in tandem, that is to say the ridge member 20 lies directly below and substantially on a line with the ridge member 19 and so the flaps 13 and 14 in the normal condition of the envelope are 30 in contact, being so held by the ridge members, which because of their rolled construction are somewhat resilient.

The ridge members, in the normal condition of the envelope, form a barrier to bar 35 egress of the contents of the envelope.

The envelope thus formed has an open end 40 defined by edges 3 and 7 of the sides and the interior flaps 13 and 14 provided with the ridge members 19 and 20. The contents may be inserted in the envelope by forcing the same into the open end 21 and past 45 the ridge members, or a slight pressure may be exerted upon the top edges as with the thumb and forefinger, by which pressure the ridge members may be slightly bowed, opening a passage between the flaps which 50 permits ready ingress into or egress of the contents from the envelope.

When the contents has been placed in the envelope, the same may be sealed if desired, 55 preferably by stapling; the ridge members forming a reinforcement which prevents the staple tearing out of the paper.

What I claim to be new is:

1. An envelope with an edge opening and a barrier positioned in said opening to obstruct egress of the contents of the envelope 60 through said opening, said barrier comprising a pair of abutments of elliptical cross-section arranged one below the other in parallel contacting relation, said abutments secured to opposite sides of the envelope. 65

2. In an envelope, an open end, a pair of flaps secured to opposite walls of and extending into the envelope from said end, one of said flaps extending to a greater depth than the other, each of said flaps having its 70 inner end rolled upon itself to form a ridge member along the inner edge of said flap.

3. In an envelope, an open end, a pair of flaps secured to opposite walls of and extending into said envelope from said end, 75 one of said flaps extending to a greater depth than the other, each of said flaps having its inner end rolled upon itself to form a ridge along the inner edge of said flap, said ridges being in juxtaposition one above the other. 80

4. In an envelope, an open end, a pair of flaps secured to opposite walls of and extending from said end, one of said flaps extending to a greater depth than the other, each of said flaps having its end rolled upon 85 itself and adhesively secured to form a ridge member along the inner edge of said flap, said ridge members being in juxtaposition one above the other.

5. The method of making an open end 90 envelope which comprises producing a blank having a pair of adjacent flaps, rolling each flap down upon itself to form a ridge member, one of said flaps being rolled a greater distance than the other, folding the flaps 95 over the inner side of the body of the blank, folding the blank to provide a back and front for the envelope and securing said back and front together.

6. The method of making an open end envelope which comprises producing a blank having a pair of adjacent flaps, coating the inner face of each flap with adhesive, rolling each flap down upon itself to form a ridge member, one of said flaps being rolled 105 a greater distance than the other, folding the flaps over the inner side of the body of the blank, folding the blank to form a back and front for the envelope and securing said back and front together. 110

In testimony whereof I affix my signature.
ALBERT E. NAUGLE.
